UNITED STATES PATENT OFFICE

JACK LOCK, OF GREENVILLE, SOUTH CAROLINA, ASSIGNOR TO JOHN E. LOCK, OF CHARLOTTE, NORTH CAROLINA

BASE PROTECTOR FOR BOBBINS AND METHOD OF ASSEMBLING

Application filed March 1, 1928. Serial No. 258,360.

This invention relates to base protectors for bobbins and method of installing the same and has for an object to provide a new and improved type of protector applied to the bobbin in a new and improved manner.

5 A further object of the invention is to provide a protector which may be employed either in new work or old work for supplying a metallic annulus to the base of a bobbin to 10 take the wear and stress of drive and also to provide a new and improved means for applying said annulus.

15 A further object of the invention is to provide a protector for the base of a bobbin so constructed that it may be applied to the bobbin without the use of fastening members of any kind, having inherent in its construction means for applying rigidly and permanently to the base.

20 With these and other objects in view, the invention comprises certain novel parts, elements, constructions, arrangements, interactions and functions, as disclosed in the drawings together with mechanical and functional equivalents thereof as will be hereinafter more fully described and claimed.

In the drawings:

Figure 1 is a view of a conventional bobbin in side elevation, the base being shown in diametrical section, to show the relation of the 30 base to the driving mechanism.

Figure 2 is an inverted plan view of the bobbin with the protector applied.

Figure 3 is a perspective view of the 35 protector before being applied to the bobbin, parts being broken out to show its construction.

Figure 4 is a view of the protector applied to a bobbin, the plane being taken on line 4—4 40 of Figure 2.

Figure 5 is a view taken on the same plane as Figure 4 but with the protector in its initial position about to be secured to the bobbin.

Figure 6 is a perspective view of the base 45 of a bobbin worn by use and in condition for practicing the method of the present invention.

Figure 7 is a diametrical sectional view taken on line 7—7 of Figure 6.

50 Like characters of reference indicate cor-

responding parts throughout the several views.

The present invention is adapted to be applied to the base of a bobbin, such term "bobbin" being used in its broadest sense to include all types of devices upon or from which yarn, thread, cordage or the like is wound or unwound and irrespective of size, configuration or use.

55 Bobbins within the above term comprise, a barrel 10 and base 11, such barrel and base being formed integral or combined in any approved manner and of any relative size or shape, and the showing of a particular type of bobbin or spool in the drawing is in no way a limitation upon the invention.

60 Bobbins are driven from a spindle 12 which occupied a spindle opening 13 in the barrel and through the base and by diametrically extending arms 14 upon the driving shaft 15.

65 Bobbins are ordinarily provided with diametrically extending slots 16 which fit upon the arms 14 and by the interaction of which the bobbin is driven. As the shaft 15 and spindle 14 rotate constantly and at a high rate 70 of speed and as the bobbin as an entirety is dropped on to the spindle while so rotating, the effect is to cut out of the bottom of the bobbin a depression 17 so that the bobbin becomes useless or of decreased efficiency.

75 The present invention is intended to be applied to bobbins in this condition or to new bobbins as may be found necessary or desirable, the method of applying and the effect being the same in either case. In either case, the diametrical slot 16 is milled out to a dovetailed transverse condition as indicated at 18, and a circumferential furrow 19 formed concentric with the spindle opening 13.

80 A protector comprising a metallic or other wear resisting plate 20 and provided with a central opening 21 is employed for protecting the base against further or initial wear. To secure this plate in position, it is formed with a diametrically positioned offset comprising the substantially parallel walls 22 and 23 joined by an upwardly struck bridge piece 24. The side walls 22 and 23 are properly spaced to slip into the narrow or outer 85 area of the diametrical slots 16 to the posi-

tion shown at Figure 5. The plate 20 is also provided with two segmental flanges 25 arcuately concentric with the central opening and occupying the circular slot 19.

5 Thus entered into the base of the bobbin a tool or implement is employed which is broadly exemplified by the die 26 to bend the web 24 from the position shown at Figure 5 to the position shown at 24' in Figures 2 and 4, whereby the walls 22 and 23 are expanded into the dove-tail slot 16 and against the side walls of said slot, and at the same time the force of the die holds the protector as an entirety in position and the depth of 10 the slot 16 relative to the dimension of the walls 22 and 23 and web 24 are such that, when expanded, the protector as an entirety is held rigidly in position and the down turned flanged edges prevent catching threads 15 or the like, also helps to strengthen the device to prevent splitting and other essential and important features.

When secured in position as indicated at Figures 2 and 4, the bobbin as an entirety is 20 used exactly in the same manner as bobbins now employed merely provided with the slots 16 formed in the material of the bobbin itself.

What I claim to be new is:—

1. The combination with a bobbin having 25 a barrel, a base, a spindle opening through the barrel and base, and a dove-tailed slot diametrically transecting the spindle opening, of a protector comprising a plate of wear resisting material having a diametrical part 30 extending and expanded into the dove-tailed slot.

2. The combination with a bobbin embodying a barrel, a base, a spindle opening in the barrel and base, and a dove-tailed slot in the 35 base transecting the spindle opening, of a protector composed of wear resisting material and formed as segments of a plate surrounding the spindle opening, said segments being connected by integral parts projected 40 and expanded into the dove-tailed slot.

3. The combination with a bobbin embodying a barrel, a base, a spindle opening in the barrel and base, a dove-tailed slot diametrically transecting the spindle opening, and a 45 furrow concentric with the spindle opening, of a protector comprising segments of wear resisting material joined by a web projected and expanded into the dove-tailed slot, and a down turned flange formed upon the arcuate margins of the segments and inserted 50 into the furrow.

4. A protector for bobbins and the like comprising arcuate segments of wear resisting material lying in the same plane, spaced 55 apart and joined by offset walls, said walls being connected by an expandable web.

5. A protector for bobbins and the like comprising arcuate segments of wear resisting material lying in the same plane, spaced 60 apart and connected together by walls sub-

stantially parallel and diametrical, said walls being joined by an expandable web, and a turned flange on the arcuate margins of the segments.

6. The combination with a bobbin having 70 a barrel, a base, a spindle opening through the barrel and base and a slot diametrically transecting the spindle opening, said slot being wider remote from than at the surface, of a protector comprising a plate of 75 wear resisting material having a diametrical part complementary to and expanded into the slot.

7. The combination with a bobbin embodying a barrel, a base, a spindle opening in the 80 barrel and base, and a slot in the base transecting the spindle opening, said slot being wider remote from than at the surface, of a protector composed of a wear resisting material and formed as segments of a plate lying in the same plane and surrounding the 85 spindle opening, said segments being connected by parts complementary to and projected and expanded into the slot.

In testimony whereof I affix my signature. 90
JACK LOCK.
